UNITED STATES PATENT OFFICE.

WILLIAM P. STUNZ, OF LANSDOWNE, MARYLAND, ASSIGNOR, BY MESNE ASSIGNMENTS,
TO THE WEBB TALKING PICTURES COMPANY, A CORPORATION OF DELAWARE.

COOLER FOR TELEPHONE INSTRUMENTS.

1,145,393.

Specification of Letters Patent. Patented July 6, 1915.

Application filed July 25, 1912. Serial No. 711,528.

To all whom it may concern:

Be it known that I, WILLIAM PRESTON STUNZ, a citizen of the United States, residing at Lansdowne, in the county of Baltimore and State of Maryland, have invented certain new and useful Improvements in Coolers for Telephone Instruments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to telephone instruments, and primarily to providing means for cooling or keeping down the heat in the granular carbon of microphone telephonic instruments, and has for its object to provide means to cover practically the whole area of the surface next to the granular carbon by a positively flowing body of cooling agent so that the burning of the electrodes next to the granular carbon will be prevented and maximum efficiency in the current obtained.

To the accomplishment of the foregoing and such other objects as may hereinafter appear the invention consists in the features hereinafter particularly described and then sought to be clearly defined by the claims reference being had to the accompanying drawings, in which two forms of the invention are illustrated, and in which:

Figure 1 is a side elevation of parts of a transmitter having a needle carrying arm and adapted for use in connection with records from which vibrations are taken by the transmitter and electrically transferred to suitable receivers; Fig. 2 is a plan view of Fig. 1, with a portion of the needle carrying arm broken away; Fig. 3 is a section on the line 3-3 of Fig. 4 through a portion of one of the carbon holding cells of a transmitter, showing the course of the flowing cooling agent; Fig. 4 is an end view of Fig. 3 with a portion of one face of the cooling chamber broken away and illustrating the arrangement of partitions in the chamber; Fig. 5 is a diagrammatic view illustrating an arrangement of cooling chambers with means for supplying and discharging the cooling agent; Fig. 6 is a sectional view, full size, through a speaking telephone transmitter

illustrating the invention applied thereto; Fig. 7 is a cross-sectional view through the receiver illustrated in Fig. 6; Fig. 8 is a detached detail view of one of the cooling chambers with portions broken away; and Fig. 9 is a diagrammatic view illustrating the front and rear cooling chambers of two granular carbon cells with means for supplying and discharging the cooling agent.

In Figs. 1 to 5 the numeral 1 designates a multiplex transmitter, in this instance, comprising four granular carbon cells 2 each containing a movable electrode 3, all of which electrodes are suitably connected to a vibratable frame 4 from which extends a vibration amplifying reducing lever 5 connected at its inner end to an arm 6 which carries a needle intended to contact with the record, said parts being laterally vibratable upon a suitable support 7, none of which parts however need be further described as they do not constitute the present invention.

In order to cool the granular carbon in the several cells, each cell is formed with a chamber 8 and provided with an inlet 9 and an exit 10 for the cooling agent which may be water or other suitable cooling agent. It is important that this cooling agent should come in contact with all portions of the wall of the chamber next to the granular carbon otherwise the granular carbon next to the points not covered by the water will become overheated and burn the electrode at such point.

To insure the proper distribution of the cooling agent I place within the chamber a series of partitions 11 arranged in such manner that the cooling agent at the point of the inlet will be directed to opposite sides of the inlet opening and caused to flow in practically two streams inwardly and outwardly in opposite directions to each other from the inlet to the outlet of the chamber thus practically covering the entire area of the chamber by two merging bodies flowing from the inlet to the outlet and traveling in laterally opposite directions. This not only causes the entire area of the wall surface of the chamber to be covered by the flowing agent but also causes a more rapid and positive flow of the agent through the chamber so that the heat absorbed from the granular carbon is very rapidly carried off and resulting in a more efficient low temperature of the carbon so that more efficiency

of current is obtained. The cooling agent is received from a suitable source into a manifold 12 from which a number of branches 13, preferably of rubber or non-conducting material, lead to the inlets of the several chambers, one branch to each chamber, and the cooling agent passes from the chambers through a number of pipes 14 preferably of rubber or non-conducting material, one from 5 each chamber, and discharging into a manifold 15 from which the cooling agent passes to any suitable point. By such arrangement it will be observed that any number of chambers are supplied from a single manifold 10 and will also discharge into a single manifold. The transmitters and cooling chambers may be all incased in a suitable casting 16.

In Figs. 6 to 8 I have illustrated the same 20 construction of cooling chamber applied to a talking transmitter. In these figures the numeral 2 designates the granular carbon cells, of which two are illustrated, each provided with a centrally disposed movable 25 electrode 3, and a cooling chamber 8 is applied at each side of each granular carbon cell instead of to only one side as in Figs. 1 to 5. Each of these cooling chambers is formed in the same way as that illustrated 30 in Figs. 3 and 4, and the cooling agent is supplied to each chamber from a manifold 17 through branches 18 and discharged from each chamber through branches 19 discharging into a manifold 20, the branches leading 35 to and from the chambers being preferably of rubber or other non-conducting material. The operation of the cooler is the same in this form as in the first form described the only difference being that in the talking 40 transmitter each granular carbon cell is provided with two cooling chambers, one on each of its two faces, and the movable electrodes are connected to a diaphragm 21, and a speaking tube or mouth piece 22 is also 45 provided.

I have illustrated and described the preferred details of construction of the various parts but it is obvious that the cooling cham-

bers formed as described may be applied to other forms of telephonic instruments than 50 those described without departing from that feature of the invention.

It is obvious that the cooling agent may be caused to flow through the cooling chamber in the opposite direction to that illustrated 55 in the drawings and be embraced within the invention.

Having described my invention and set forth its merits what I claim is:—

1. In a telephonic instrument, a granular 60 carbon chamber provided with a cooling chamber having partitions arranged to cause a cooling agent to flow in practically a plurality of streams through the chamber, each in a circuitous path.

2. In a telephonic instrument, a multiple 65 of granular carbon chambers each provided with a cooling chamber having partitions arranged to cause a cooling agent to flow in practically a plurality of streams through 70 the chamber, each in a circuitous path, a supply manifold with branches leading therefrom to the multiple of chambers, one to each chamber, and branches leading from the chambers to a discharge manifold.

3. In a telephone instrument, a plurality 75 of granular carbon cells each having a centrally disposed movable electrode, a diaphragm with which the several movable electrodes are connected, a cooling chamber 80 on the opposite sides of each granular carbon cell, each cooling chamber being provided with partitions arranged to cause a cooling agent to flow in practically a plurality of streams through the chamber, each 85 in a circuitous path, means for supplying the cooling agent to each chamber, and means for discharging the agent from each chamber.

In testimony whereof I affix my signature 90 in presence of two witnesses.

WILLIAM P. STUNZ.
